TELECOMMUNICATIONS SYSTEM

William G. H. Finch, New York, N. Y.

Application February 26, 1936, Serial No. 65,869

11 Claims.

(CL 179—4)

My invention relates to telecommunications systems and more particularly relates to novel apparatus for and methods of transmission of pictures to remote points.

The widest use which telepicture systems today enjoy is in connection with newspaper service where pictures of important news events are transmitted from or near its source to newspaper offices for publication. For such use, it is highly desirable that the picture be transmitted as near to the scene as practicable. Heretofore, it has been proposed to use telephone lines which are usually available at almost any place for the transmission of pictures. Inasmuch as the telephone company, however, generally does not permit any interconnection by a subscriber to its lines, it has been necessary to find some other than physical connection means for transmitting picture signals over the telephone lines. It has been proposed that this might be accomplished by acoustic coupling to the telephone line. Such a system comprised a loud speaker unit which transformed picture signals into corresponding sounds which in turn were impinged on the usual telephone microphone.

Although the acoustic method of inducing picture signals into the telephone line has still been proposed as recently as within the past few years, it has many inherent defects which render it impractical. The more serious of the many drawbacks of such an arrangement are the distorted frequency response characteristic of the usual loud speaker, and the even more distorted frequency response characteristic of the carbon microphone ordinarily used in telephone systems. Although for the transmission of speech, poor frequency characteristics are not material, as the ear tends to correct for audible distortions, they are serious in connection with telepicture systems where distortion would be visibly evident on the received picture.

I have discovered a novel electric coupling to the telephone lines which has a linear frequency characteristic with respect to the signals transmitted thereby. Specifically, my system contemplates a novel method of inductively inducing picture signals into the telephone line at the transmitter by a novel portable member which may be applied to any telephone subscriber station call box.

The transmission of low frequencies, for example, frequencies below 25 cycles, is greatly attenuated in present telephone systems. Communication requiring signals below 25 cycles may accordingly not be directly transmitted thereby.

By modulating an audio frequency carrier wave with such signals, they may then be readily transmitted over the telephone system. The original telecommunications signals are then obtained by demodulation at the receiver. The electrical inducing means of my present invention provides for the linear transmission and reception of such carrier signals. In telegraphy, printing telegraphy and picture transmission systems, such audio frequency carrier operation is preferable.

By establishing a linear wide frequency band transmission characteristic, for example, linear from 25 cycles to 5000 cycles, over a telephone line, it is possible to transmit two independent telecommunications signals utilizing two independent audio frequency carrier waves. Simultaneous speech and telegraph or printing telegraph and telepicture transmission over a single telephone channel is accordingly practical without physical connection thereto, according to my present invention.

Among the advantages other than the well known economic advantages, of utilizing a telephone system for telecommunications which my novel coupling means makes available, is the utilization of a portable transmitter. A newspaper reporter, for example, provided with my novel coupling arrangement may be provided with a portable transmitter which he can employ at any telephone station for transmitting to his main office a picture which has immediate news value. In doing so, he will in no way interfere with the normal operations of the telephone line other than to utilize it as any subscriber when he lifts the phone off the hook.

In a further modification of my invention, I contemplate transmitting the signals of the portable transmitter induced into the telephone line to the nearest of a number of strategically placed radio transmitting stations for the purpose of either simultaneous or subsequent transmission of the picture signals from such station. This arrangement would not only reduce the telephone costs but would also provide quicker service for national coverage.

In a still further modification of my invention, I contemplate a portable transmitter which radiates a short wave signal modulated in accordance with the picture signals to be received by the nearest of the strategically placed radio stations for retransmission either simultaneously or subsequently as desired. Inasmuch as these transmitting stations are placed at centralized points of activities of a national newspaper service, the range of

the portable radio transmitter need not be very great and accordingly makes possible a relatively light, low-powered unit. At the same time, as distinguished from telephone system transmission, the radio transmission by the portable unit in conjunction with the nation-wide newspaper radio hook-up may simultaneously provide the picture at each of these radio stations.

Moreover such a portable radio telepicture transmission unit may, by the provision of simple switching arrangement be immediately converted for electrically inducing picture signals into the telephone line in the type of telephone coupling system described hereinabove.

Both in the case of the modulated carrier signals over the telephone lines and in the case of the radio carrier transmission provision is made for automatic signal level control, in a manner well known in the art, to compensate for any variations in the transmission characteristic and insuring a properly shaded received telepicture.

It is accordingly an object of my invention to provide novel methods of and means for electrically coupling to public telephone systems for the transmission and reception of signals between remote points.

Another object of my invention is to provide novel methods of and means for transmitting pictures over a telephone system.

A further object of my invention is to provide novel methods of and means for transmitting telecommunications signals across telephone lines, by modulating an audio frequency carrier wave and electrically inducing the resulting signals into a telephone system.

Still a further object of my invention is to provide novel methods of and means for transmitting pictures over a telephone line utilizing an audio frequency carrier wave which is electrically induced into the telephone system.

Another object of my present invention is to provide novel methods of and means for electrically coupling a telepicture receiver at a telephone receiving station for receiving signals without physical interconnection with the telephone system.

Another object of my invention is to linearly transmit two or more independent or interdependent telecommunications signals over a single telephone line without physical connection thereto.

A further object of my invention is to provide a novel system for the transmission of telepicture signals from a portable transmitter by electrical coupling to a local telephone line to the nearest of a group of radio transmitters for simultaneous or subsequent retransmission thereby to other receiving stations.

Still a further object of my invention is to provide a novel system of telepicture transmission whereby a portable radio transmitter radiates the telepicture signals to one or a group of radio transmitters for simultaneous or subsequent retransmission.

In the transmission of pictures to remote points it is essential that the receiver picture drum be in phase synchronism with the transmitter drum. Many attempts have been made to attain such phase synchronization. It is extremely desirable to provide a positive driving connection between the motor and the revolving drum to avoid any deleterious effects due to friction coupling. In my Reissue Patent No. 19,575, I have disclosed a system for connecting and disconnecting the positive driving connection between the driving motor

and the drum in response to synchronizing signals to maintain phase synchronization. In my present invention I utilize an over-running or positive clutch with means responsive to the synchronizing signals for maintaining the drum in phase synchronism. In one embodiment I revolve the receiving drum at a slightly higher rate than the transmitter drum, in the ratio of 101 to 100, so as to establish the synchronizing pulse at a predetermined portion of the receiving drum, which portion will accordingly always be in position due to the increased speed ratio, to receive the synchronizing impulse.

To overcome the effects of rotational inertia present in a large telepicture system having a large revolving drum, I provide a flexible mechanical coupling between the positive clutch and the receiving drum which permits momentary phase displacement due to accelerating or decelerating inertial forces and promptly automatically compensates for momentary phase displacements.

A further object of my present invention is to provide a novel telepicture synchronizing system utilizing an overrunning or positive clutch at the receiving station.

Still a further object of my invention is to provide a mechanical flexible coupling in the positive drive for a revolving drum, which automatically compensates for any momentary phase displacement due to acceleration or deceleration forces.

Another object of my invention is to provide a novel method of and means for rapid removal or insertion of the picture drum in a telepicture apparatus.

Still another object of my invention is to provide a novel method of and means for motivating the scanning mechanism.

Another object of my invention is to provide novel methods of and means for substantially eliminating transverse vibration of the scanning mechanism in a telepicture transmitter or receiver.

Other objects of my invention together with the foregoing will become apparent in the following description taken in connection with the drawings in which:

Telecommunications system

65 Figure 1 is a schematic illustration of the telecommunications system according to my invention. Transmitter 1 may be a telegraph, printing telegraph, speech or telepicture signal generator. The audio frequency generator 1a is modulated by the generated telecommunications signals of transmitter 1 in a well-known manner, to provide an audio frequency carrier for the signals to be transmitted. The output of the transmitter 1 is connected to an audio frequency amplifier 2 by connection leads 3-4. The

output of the audio frequency amplifier 2 may be transmitted to a remote receiving station by the direct wire lines 5-6. Closing switch 1 on contact 8 connects the wire lines 5-6 in circuit.

An audio frequency amplifier 10 is used at the receiving station for amplifying the signals at the receiving end of the transmission line 5-6 to the amplitude necessary for actuating the translator 11. Receiving switch 12 is closed on contact 13 for operating the receiving station 10 from the land lines 5-6 as is understood. The translator 11 is an apparatus corresponding to the type of telecommunications transmitter 1 used. For example, if a picture is to be transmitted by transmitter 1, translator 11 will be a telepicture receiver designed to translate the telepicture signals in accordance with the picture being transmitted. The audio amplifier output leads 14-15 connect the output of amplifier 10 to the translator 11. In some applications it may be necessary to demodulate the signals so as to separate the generated transmitter 1 signals from the audio frequency carrier of 1a. Such a demodulator is well known in the art, and is included in the translator 11 of my schematic illustration.

The telecommunications system of Figure 1 will operate across a radio channel 16 when the transmitter switch 7 is closed on contact 17, and the corresponding receiver switch 12 is closed on contact 18. The output of audio amplifier 2 is introduced by leads 20-21 to the radio frequency modulator 22. The radio frequency oscillator 23 provides the radio frequency carrier for the radio frequency signals to be transmitted. The output of modulator 22 is connected to radio frequency amplifier 24. The radio frequency signals are radiated by antenna 25 connected to the output of radio frequency amplifier 24.

At the receiving station, antenna 26 is impressed by signals from transmitter antenna 25 across the radio channel 16. A radio frequency receiver 27 amplifies signals from antenna 26. The radio frequency receiver 27 may be tuned radio frequency amplifier, or a superheterodyne receiver. The output of the receiver 27 is connected to a demodulator or detector 28 for demodulating radio frequency signals. The audio frequency signals corresponding to those at the audio amplifier 2 are accordingly produced at the output 30-31 of the detector 28. The receiving switch 12 being closed on contact 18, audio amplifier 10 will be impressed with the corresponding audio frequency signals for their amplification to a level to properly actuate translator 11.

A further method of transmitting the telecommunications signals is schematically illustrated by the electrical induction means, into a public telephone system, forming a primary object of my present invention. The transmitter switch 1 is closed on contact 32 and the corresponding receiving switch 12 is closed on contact 33. The output of audio amplifier 2 is impressed upon leads 34-35 through an optional compensating network 36, the output leads 37-38 of which are connected to solenoid 40. Solenoid 40 is placed adjacent the ordinary local telephone box 41 associated with the telephone 42-43 at the transmitting station.

An indication coil 44, shown in dotted lines within the phone box 41, is associated with each telephone unit 42-43. The signals to be transmitted produce a magnetic field about solenoid 40. This magnetic field is induced in the induction

coil 44 for transmission along the telephone lines 45-46 as will be hereinafter described in more detail. The phone box 41 of the receiving station contains the corresponding induction coil 48 of the receiving telephone 49-50.

When the telephone circuit between the telephone stations 42-43 and 49-50 is established through an automatic telephone connection or by a telephone operator, the telecommunications signals induced into induction coil 44 by transmitter solenoid 40 are received by the receiver induction coil 48. The signals through induction coil 48 produce a corresponding magnetic field about the induction coil 48, and the receiver solenoid 51 placed in this magnetic field has induced therein a voltage corresponding to the transmitted signals. The receiver solenoid 51 is connected to the audio amplifier 10 by leads 52-53 across contact 33 and through switch 12. The signals amplified by audio amplifier 10 accordingly correspond to those at the transmitter amplifier 2. The amplified signals are introduced to the translator 11 by leads 14-15.

The electromagnetic inducing method for transmitting and receiving telecommunications signals provides a practical system for utilizing existing telephone communication systems for transmitting without interconnection thereof. The signals are transmitted and received electromagnetically, or, as in a hereinafter described modification, electrostatically across the telephone lines 45-46. Transmission characteristics of such a system may be made substantially linear with frequency as will be hereinafter further explained.

An important feature of the telecommunications system according to my present invention is the use of a portable transmitter for efficiently relaying a message or picture to a central office. Figure 1A is a schematic illustration of a modification of Figure 1, illustrating such a transmitter system. The portable transmitter is designed to be rugged and light in weight so that it may be manually transported, and operated from an automobile, airplane, ship, or the like. The portable transmitter should preferably be operable from storage batteries and from standard power lighting circuits by suitable selective switching.

For newspaper work it is very desirable to have a telepicture transmitter which an operator or reporter carries to the scene where pictures are to be taken. The developed picture is inserted into the telepicture transmitter, and the corresponding picture signals are transmitted to the nearest newspaper station in a manner to be described. A newspaper service may have a plurality of radio transmitter and receiver stations positioned at strategic locations over the nation. These radio stations are equipped to receive and transmit telepicture signals. The portable telepicture transmitter 1' is connectible to either a portable short wave transmitter 8, or to a solenoid 40 for inducing the telepicture signals across the telephone lines 45-46.

The operator of the portable transmitter 1' may, for example, transmit a picture of immediate news value to his nearest newspaper office from a telephone subscriber station. He phones from his station 42-43 to the station 49-50 of his office. The switch 7' of the transmitter is closed across contact 32' so that the telepicture signals are impressed upon solenoid 40. The solenoid 40 is placed in operative relation with the induction coil 44 in phone box 41 at the local subscriber

station 42-43. The telepicture signals from the output 3'-4' of transmitter 1' will accordingly be inductively induced across telephone circuit 45-46 to the newspaper office telephone station 49-50.

The induction coil 48 in the phone box 41 will carry the telepicture signals and electromagnetically impress them upon the pick-up solenoid 51. The switch 12' at the newspaper office is closed on contact 33' so that the signals picked-up by solenoid 51 are impressed upon audio amplifier 10' through leads 52-53. The telepicture signals are then impressed upon the telepicture translator 11' which reproduces the picture being transmitted by the transmitter 1'.

It may be desirable to simultaneously re-radiate the picture signals being radiated by the portable transmitter 1' by a powerful radio station transmitter for reception at distant newspaper receiving stations. The output of the audio amplifier 10' is connected to the relatively powerful radio frequency transmitter 29 which radiates a radio frequency carrier wave modulated in accordance with received picture signals over antenna 39.

In many instances a telephone subscriber station may not be available to the operator and accordingly I provide a modification for transmitting picture signals to a newspaper office by a portable radio transmitter. The useful range of such a transmitter may be several hundred miles so that a corresponding short wave receiver at the newspaper office may properly receive the picture signals. The radio picture relaying modification is illustrated in Figure 1A in conjunction with the portable short wave transmitter 8 and the newspaper short wave receiver 19.

The transmitter switch 7' is closed upon contact 17' and the telepicture signals from transmitter 1' are conducted to the input 20'-21' of the portable short wave transmitter 8 for modulating its carrier wave which is radiated by antenna 25'. It is to be understood that the portable short wave transmitter 8 is designed along the lines of the portable telepicture transmitter 1' with respect to the type of power supply, weight, and so forth.

The modulated short wave carrier transmitted along radio channel 16' is received at the newspaper office short wave receiver 19 by antenna 26'. The short wave receiver 19 should be designed to properly receive the signals from the portable transmitter 8 corresponding to a distance that the portable transmitter may be operating from the office. Receiver 19 contains a demodulator for the short wave carrier, and introduces telepicture signals to the input of the audio amplifier 10' by leads 30'-31' when the switch 12' is closed to contact 18'. The signal input to audio amplifier 10' corresponds to the signal output of portable telepicture transmitter 1' at 3'-4'.

The telepicture signals at audio amplifier 10' may be locally reproduced by translator 11', and may also be simultaneously re-transmitted by the powerful station radio-frequency transmitter 29 over antenna 39. It is to be understood that the transmission of pictures from the radio station 29 may occur simultaneously with the reception of the picture from the field portable transmitter 1' as herein described, or may be subsequently transmitted from the reproduced picture as obtained from the telepicture translator 11'. The use of simultaneous re-radiation over a more powerful radio-frequency carrier wave of picture signals having immediate news value as received

from a field portable telepicture transmitter makes possible a cheap, efficient and rapid national coverage of the particular picture to all the newspaper receiving offices strategically located over the country.

Figure 2 is a schematic illustration of the telephone system 43-50 in operative relation, including the connections between transmitter microphone 54 and ear-piece 55 to the phone box 41 by leads 56, 57, and 58, the connections to the receiver phone box 47 across lines 45-46; and the connections to the receiver microphone 60 and earphone 61 by leads 62, 63, and 64. I have here illustrated one of the several methods in which the induction coils 44 and 48 are generally connected in telephone systems. The particular connections of the induction coils in the system are not important, since in every case the effects described in conjunction with the illustrated connections will be effected. The dashed portion 45'-46' of the telephone line 45-46 represent all the auxiliary apparatus necessary to maintain the telephone stations 43 and 50 in operative relation. Included between the stations 43 and 50, as is well known, are repeating stations, batteries, ringers, etc.

At the transmitter station, the microphone 54 is connected to line 45 by lead 56. The microphone 54 circuit is completed by lead 57 to the line 46, with the primary 65 of induction coil 44 connected in series therewith. As is well known, the carbon microphone 54 requires a direct current energization which is supplied through the last mentioned series circuit arrangement. The telephone earpiece 55 is coupled in this manner to the telephone lines to eliminate the passage of direct current therethrough. The earphone 55 is connected to the secondary 66 of the induction coil 44 by lead 58. The opposite side of the secondary 66 is connected to line 45 in series with the condenser 67. The primary 68 and secondary 69 of the receiver induction coil 48, together with condenser 70 are connected at the receiver microphone 60 and earpiece 61 in a manner similar to that at the transmitter 43 herein described.

The transmitter solenoid 40 is placed adjacent to the induction coil 44 to provide for optimum induction of the telecommunications signals therein. I have found that when the axis 71 of solenoid 40 coincides with the axis of the induction coil 44 maximum signal energy transfer is had. The solenoid 40 is placed as close as practicable to the one end of induction coil 44 to insure maximum signal induction. The phone box 41 is enclosed by a sheet metal cover 72 indicated in dotted lines in Fig. 2. In a practical performance of the coupling arrangement according to my invention therefore, one side of the solenoid 40 is juxtaposed with the metal cover 72 at a region so that its axis coincides with the induction coil 44 axis, or is as close thereto as physical conditions permit.

The region of optimum coupling is determined in the following manner. The audio frequency carrier or tone from generator 1a is introduced to the line through amplifier 2 (Fig. 1) and impressed upon solenoid 40 as hereinabove described. This operation is preliminary to the transmission of the telecommunication signals for optimum adjustments of the transmitting and receiving apparatus. Telephonic communications between stations 43 and 50 are established through automatic dialing or by telephone operators. The solenoid 40 is placed close to one end

of the induction coil 44. The tone or audio frequency carrier may be heard locally by the transmitter operator through earpiece 55. The position of solenoid 40 is adjusted on box 41 with respect to induction coil 44, so that a tone of maximum intensity is heard by the operator in earpiece 55. A rapid and simple determination of the optimum coupling position is had in this manner.

The solenoid 51 at the receiving station is positioned for a maximum signal transfer or pickup with respect to induction coil 58. This position is determined in a manner similar to that described at the transmitter, namely the axis of solenoid 51 preferably coincides with the axis of induction coil 48, and one end of solenoid 51 is juxtaposed on the metal casing 75 of the receiver phone box 47. The receiving coil 51 is experimentally adjusted to this optimum position by listening to the tone in earpiece 61 and is rigidly clamped in place as herein described. Such adjustment is preferably made during the transmission of a constant amplitude carrier from the transmitter. The optimum position may more accurately be indicated by an output meter (not shown) connected at the audio amplifier 10 as will be evident to those skilled in the art.

Figure 3 is a graphical representation of a typical overall transmission characteristic which I have obtained between a transmission and receiving station, corresponding to signals at the transmitter 1 and translator 11 of Fig. 1. The curve 76 was plotted with frequency, in cycles per second, and with E, representing the received voltage at the translator 11. At the transmitting station 4 signals of constant amplitude were introduced to the audio amplifier 2 at frequencies extending from 25 cycles to 5000 cycles and beyond. Curve 76 demonstrates the substantial linearity of this method of transmission from 900 cycles to 5000 cycles as indicated by the corresponding horizontal portion of the curve 76. However, a peak 77 occurred in the region of 400 cycles, starting at 25 cycles rising to a maximum at about 400 cycles, and diminishing to the flat characteristic portion of curve 76 at about 800 or 900 cycles. With the transmission characteristic illustrated in Fig. 3, an audio frequency carrier of 3000 cycles may be used to transmit telecommunication signals with no frequency discrimination for the sidebands of the 3000 cycle carrier as will be understood by those skilled in the art.

If intermediate equipment between the telephone stations 43 and 50 introduce a cut-off frequency below 5000 cycles to the transmission characteristic, the audio frequency carrier may accordingly be adjusted so that the sidebands may be uniformly transmitted. It is also practical to transmit a single sideband upon an audio frequency carrier, and utilize the linear transmission characteristic on single side band audio frequency carrier transmission as is well known in the art.

Another important feature of my invention resides in extending the linear characteristic transmission relation from 25 cycles, by eliminating the effect of the peak 77 by inserting a compensation network 36 between the transmitter solenoid 40 and the transmitter amplifier 2 output. The purpose of this network is to attenuate signals between 25 cycles and 900 cycles inversely proportional to the peaked relation 77 of Fig. 3. In Fig. 2 I illustrate a simple form of compensation network for this purpose. An inductance 36a and capacitance 36b are connected in series across

solenoid 48 connection leads 37-38. The inductance 38a and capacitance 38b are designed to be tuned to 400 cycles in a manner well known in the art. The compensation network will absorb signals to the greatest extent at the frequency it is tuned to, namely, 400 cycles, to correspond to the peak of the induction coupling system herein described.

Fig. 4 illustrates the transmission characteristic 71 of the compensation network 38. It will be seen that minimum transmission occurs at 400 cycles. The proportion of transmission decrease is made equal to the ratio of the peak 71 to the plateau 6 of Fig. 3.

Fig. 5 represents the overall transmission characteristic 80 corresponding to Fig. 3 with the compensation network 38 connected as illustrated in Fig. 2. The super position of compensation network characteristic 78 of Fig. 4, upon the transmission of characteristic 77-78 of Fig. 3, produces the transmission characteristic 80 of Fig. 5 which is substantially linear from 25 cycles to 5000 cycles and above.

It is accordingly evident that the electrical induction method for transmitting audio frequency signals according to my present invention, may be attained with substantially no amplitude discrimination with respect to the frequency. I have also found that the noise level of this transmission system is negligible as compared to the telecommunications signal strength, resulting in an excellent signal to noise ratio.

The wide channel afforded by my present invention with no physical connection to telephone lines, may be utilized with more than one carrier wave transmission. Accordingly, in Fig. 5 I have illustrated two audio frequency carriers, namely carrier No. 1 and carrier No. 2. Carrier No. 1 may, for example, be a tone of 1500 cycles, and carrier No. 2, a tone of 3500 cycles. The flat frequency characteristic 80 of the system permits the side-bands of the carriers Nos. 1 and 2, representing independent or interdependent telecommunications signals to be transmitted without any signal discrimination.

The utilization of two carriers as herein described may be for simultaneous telegraphy and printing telegraphy, or telegraphy and speech, or teletypewriter and speech, or the simultaneous transmission of two independent similar systems, for example, two facsimile pictures being simultaneously transmitted. Another modification for utilizing the wide audio frequency channel with two independent audio frequency carriers is to simultaneously transmit adjacent lines of a picture being scanned with two scanners oppositely disposed upon the picture drum, so as to cut in half the time for transmitting a single picture. Such a system requires each of the audio frequency carriers to be associated with one of the corresponding alternate scanning lines of the picture being transmitted, to actuate corresponding alternate teletypewriter translators for simultaneously reproducing the predetermined alternate picture lines at the receiver.

It is to be understood that suitable filter means are necessary at the receiving station for properly directing the two independent audio frequency carriers to their predetermined respective translators.

Another modification resides in transmitting a plurality of tones suitably spaced along the audio frequency transmission channel for actuating a printing telegraph apparatus. A plural-

ity of tones are simultaneously transmitted, corresponding to, for example, a Baudot code combination for each character of a printing telegraph system. Corresponding filters at the receiving station are used to segregate the respective constant frequency tone impulses, to actuate the printing telegraph receiver. Such a system of simultaneous tone combinations greatly increases the speed of printing telegraph transmission in comparison to successive transmission of the impulses of the code combinations.

Another modification is to utilize the peaked portion 71 of the characteristic illustrated in Fig. 3 for transmitting synchronizing impulses. A four hundred cycle note corresponding to the frequency of the peak 71 is intermittently impressed upon the transmission line for synchronizing the telecommunications receiver and transmitter. For example, in a teletypewriter system, a synchronizing impulse is sent at the beginning or end of each line being scanned for maintaining synchronism of the revolving drums. The synchronizing impulse is generally of increased intensity for operating a marginal synchronizing relay. In this modification, however, the synchronizing impulse at the transmitter need only be of normal intensity. The uncompensated induction transmission characteristic will impress the synchronizing note of 400 cycles at an increased relative amplitude to operate the marginal synchronizing relay.

Fig. 6 is a cross-sectional illustration of a clamp for rigidly attaching the transmitter solenoid 48 upon the phone box 41. The induction coil 44 is supported within the phone box 41 by wooden uprights 81. The core of the induction coil 44 comprises laminated metal strips 82 which generally project into the wooden uprights 81. One end of the bracket 83 is attached to the solenoid 48 by screws 84. A threaded rod 85 passes through a hole at the opposite end of the bracket 83 and a thumb screw 86 is operated to press bracket 83 against a collar projecting from the corresponding end of clamping bracket 87. Bracket 87 is placed around the corners of phone box casing 72. By manipulating the thumb screw 86 at the end of threaded rod 85, the solenoid 48 is rigidly fastened in position upon the phone box 41. The iron core 78 of solenoid 48 is preferably positioned in axial relation with the iron core 82 of induction coil 44 in a manner hereinabove described. The receiver solenoid 51 has a similar arrangement for fastening to the receiving phone box 47. In my preferred embodiment the receiver solenoid 51 has an air core.

Fig. 7 is a modification of the electromagnetic inducing arrangement illustrated in Fig. 2. Two solenoids 48 and 48a are arranged at opposite ends of the induction coil 44 so that the induction coil 44 has signals induced at opposite ends. A greater efficiency of electrical induction is had by such an arrangement. The solenoids 48 and 48a contain laminated iron cores 78 and 78a respectively. A common iron yoke 88 supports the solenoids in position upon the phone box 41. Both ends of the yoke 88 may be constructed similar to that of bracket 87 of Fig. 6 for properly supporting coils 48 and 48a in the optimum position upon the phone box casing 72.

It is to be understood that the polarities of the solenoids 48 and 48a are arranged to induce the electrical signals into induction coil 44 in additive relation. At the receiving station phone box 47, two pick-up solenoids 51 and 51a are disposed on opposite sides of the induction

coil 42 in additive relation in a manner similar to the transmitter solenoids 40 and 40a herein described. The electrical signals in solenoids 51 and 51a are connected to the receiving apparatus through leads 52 and 53 as illustrated in Fig. 1, through contact 33 of switch 32. The arrangement of two oppositely disposed pick-up solenoids provides at least twice the signal pick-up as compared to the use of a single solenoid.

10 The energy levels of the signals induced into the telephone system at the transmitter induction coil 44 is limited by the magnetic saturation of the iron core 82 induction coil. To avoid signal distortion due to overloading of the telephone lines, the maximum signal intensity transmitted is kept below the predetermined distorting intensity. Interference due to "cross-talk" is also minimized in this manner. The intensity of the telecommunications signals induced into the telephone system according to my invention is comparable to the peak voice signal intensity transmitted by the telephone line. Such signal level is transmitted with an extremely favorable signal to noise ratio so that subsequent amplification is feasible for quality intercommunication.

15 Although I have described preferred electromagnetic coupling methods which provide the most efficient and best transmission characteristic for transmitting telecommunications signals across a telephone system without physical connection thereto, other electrical coupling methods are feasible. For example, the signals may be induced into the telephone earpiece windings or other parts of the local telephone station.

20 However, the concentration of the winding turns at the induction coil provides the most practical point for electromagnetically inducing the signals. Preferred methods of electrostatic induction of telecommunications signals into a telephone system is illustrated in Figs. 8, 9, and 10.

25 Fig. 8 illustrates a metallic plate 86 connected to one terminal of the output of the audio frequency amplifier 2 of the telecommunications signals to be transmitted. The audio frequency amplifier, as hereinabove described, is connected to the switch 7 which is closed on contact 32 for connecting the output of amplifier 2 to the leads 32 and 35 connected to the input of the compensation network 36. The characteristic of the compensation network 36 is designed to compensate for the frequency discrimination presented by the particular electrostatic induction method used according to principles well known in the art.

30 The output of audio frequency amplifier 2 is preferably of a high voltage to place the plate 86 at a high electrostatic potential with respect to ground. The lead 38 from the output of compensation network 36 is connected to plate 86; the other lead 37 being connected to ground. Fig. 8 shows a hand set desk telephone positioned upon the plate 86 in operative condition, the hand set 43 being removed from its position on the telephone stand 42. An automatic telephone dial 81 is shown in the telephone base 42. Telephone cable 82 corresponding to leads 56, 57, and 58 of Fig. 2 connects the telephone instrument 42-43 to the phone box 41. Leads 45 and 46 of the output of phone box 41 connect the instrument to the remainder of the telephone system as described hereinabove. The metallic plate 86 is isolated from ground. The telecommunications signals impressed upon the audio amplifier 2, as described in connection with Fig. 1, are electrostatically induced to the telephone system, thru

the telephone base 42 and hand set 43, no physical interconnection being necessary. The signals are transmitted over lines 55-56 to the receiving station to be received as hereinabove described.

Figure 9 is a practical embodiment of a transmitter using the electrostatic induction principle of Fig. 8. A transmitter cabinet 93 housing a signal generator, for example, a portable telepicture or facsimile transmitter, contains a metallic plate 94 set into the insulation cover 95 of the cabinet 10 10 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290

93. Cover 95 may, for example, be wood, hard rubber or other insulation material. The telephone base 42 is placed upon the metallic plate 94. It is also feasible to provide room for the hand set 43 on plate 94, although it is not necessary. 15 Plate 94 corresponds to plate 90 of Fig. 8 and is connected to the lead 38 of the electrical circuit. Figure 10 is another embodiment for electrostatically inducing telecommunications signals into the telephone system. The portable tele- 20 communications transmitter 96 contains a compartment 97 at one side thereof into which the telephone 42 may be inserted. Compartment 97 is lined with a sheet metal 98 such as copper, to provide the electrostatic inducing surface corre- 25 sponding to plate 90 of Figure 8. The lining 98 is insulated from the remainder of the receiver, and the material 98 to which it is fastened is wood or other insulation. The embodiment of Fig. 10 provides electrostatic induction by sur- 30 rounding the telephone apparatus. The hand set 43 may optionally be inserted in compartment 97.

The electrical inducing methods hereinbefore described make it possible for a portable telecommunications transmitter, for example, a telepic- 35 ture transmitter, to transmit a picture which may have immediate news value from any telephone station to the central newspaper plant by merely establishing a telephone connection between the stations, verbally establishing the conditions of 40 the transmission, and proceeding to transmit the picture in a manner already described. The tremendous commercial advantage, particularly to newspaper offices, of such an arrangement is self-evident. No permanent leasing of telephone lines 45 between permanent stations is required. Payment for the use of the line is according to the actual time taken in transmitting the picture instead of over a 24 hour period as is at present required.

By employing the two channel transmission method hereinabove described in connection with Fig. 5, simultaneous printing telegraph and telepicture transmission may be carried on between the stations, so that the news story in connection 55 with the picture may be had. A further method is to employ the frequency range from 25 cycles to 2000 cycles for an intelligible speech channel, in place of carrier No. 1 (of Fig. 5), and simultaneously use carrier No. 2 at 3500 cycles for the 60 telepicture transmission. The verbal news story is accordingly manually transcribed at the newspaper office during the picture transmission, economizing by saving valuable line time.

Telepicture transmitter

Figure 11 is a schematic electrical diagram for an improved telepicture transmitter according to my present invention. This transmitter is to be used for transmitting pictures with the telecommunications system indicated in Figure 1 and hereinabove described.

A source of light 100 produces a beam 101 focused to a point by a lens system 102 upon the picture to be transmitted which is mounted on 75

the cylindrical drum 103. If the picture is scanned one hundred lines per inch, the diameter of the light spot focused upon the picture should be .01 inch. The refracted beam 104 from the picture is focused upon the photoelectric cell 105 by lens system 102'. The intensity of the refracted beam 104 is proportional to the shading of the picture elements which are successively moved past the light beam 101. The picture drum 103 is rotated by shaft 106 driven by synchronous motor 107. Motor 107 is preferably connected to a commercial electrical supply system 108, for example, a 60 cycle, 110 volt system. Reduction gearing, not shown, reduces the motor 107 speed to, for example, 100 revolutions per minute at shaft 106.

The anode potential for the photoelectric cell 105 is supplied by the potentiometer 109 connected across a suitable direct current voltage source 110. Condenser 111 by-passes the potentiometer 109 section to ground. The cathode 112 of the photoelectric cell 105 is connected to the control grid 113 of a screen grid modulator tube 114 by means of connection lead 115. The control grid 113 is adjustably biased by means of potentiometer 116 connected across a suitable grid biasing source 117. The grid bias for control grid 113 is supplied from the potentiometer 116 through the grid input resistance 118.

Screen grid 119 is connected to a suitable potential point on the direct current source 120 through an impedance choke 121. The anode 122 is connected to the potential source 120 through an impedance choke 123. A tone generator 1a, schematically indicated, produces an alternating current potential across two potentiometers 124 and 125. The tone generator 1a may be an audio frequency vacuum tube oscillator, or an alternating current generator driven by an electric motor. The alternating current signal from tone generator 1a is coupled to the screen grid 119 through a coupling condenser 126. The impedance choke 121 prevents the tone signal from being by-passed to ground through the potential source 120.

The varying light beam 104 produces corresponding electrical variations at the control grid 113 of vacuum tube 114 as is well known in the art. Introducing a tone or carrier signal from generator 1a to the screen grid 119 corresponds to the well known screen grid modulation method. The signal produced in the output circuit of the vacuum tube 114 across the impedance choke 123 is coupled to the control grid 127 of amplifier stage 128 by means of the coupling condenser 129. A milliammeter 130 inserted in series with the anode 122 circuit in lead 123 serves as a visual indication of the operating condition of the telepicture transmitter.

When no light impinges upon the photo cell 105, the control grid 113 has a potential corresponding to the adjusted bias by potentiometer 116 and the tone or carrier signal output of the vacuum tube 114 will be at a minimum. The indication of the milliammeter 130 will accordingly also be at a minimum. When a bright spot is scanned on the picture being transmitted, the potential of control grid 113 will correspondingly increase. The anode 122 current will therefore also increase. The indication of milliammeter 130 will correspondingly increase. The alternating current or carrier current output proportionately increases as is well known to those skilled in the art. Meter 130 accordingly indicates the functioning of the telepicture transmitter.

The control grid 127 of amplifier tube 128 is

impressed with an alternating current signal of the generated tone 1a frequency modulated in accordance with the varying intensity of the light beam 104 impinging on the photo cell 105. The grid bias for control grid 127 is supplied by the bias battery 131 connected to the grid 127 through grid resistor 132. The primary of audio transformer 133 is connected in the output circuit of amplifier 128. The secondary of transformer 133 is connected by leads 3-4 to the input of audio 10 amplifier 2 shown in Figure 1, for further amplification of the telepicture signals for transmission to a remote station.

Synchronization of the transmitter and receiver picture drums is accomplished by means of a synchronizing signal transmitted during each revolution of the transmitter drum 103 for controlling the synchronizing mechanism at the receiver to be hereinafter described. I prefer to transmit the tone or audio carrier signal of intensity greater than the maximum picture signal intensity for the cyclic synchronizing signals. In Figure 11 I schematically illustrate a preferred method for producing the synchronizing signals. The potentiometer 125 is adjusted for a suitable tone voltage to be intermittently impressed upon the control grid 127 through coupling condenser 134.

The synchronizing signals are transmitted during a small predetermined portion of the time required for each revolution of the drum 103. A cam 135 attached to the drum shaft 106 actuates the contact blade 136 of a cam switch. Projection 137 of the cam 135 closes the cam switch circuit blades 136-138 which are connected in series with the leads 139 and 140 from the potentiometer 125 to the coupling condenser 134. The angular position of cam projection 137 corresponds to the "dead" or underlap portion of the picture drum 103 where the "dead" edges of the picture being transmitted are fastened by clamping members to be hereinafter described. A carrier voltage preferably of increased intensity as compared to the maximum telepicture signals is accordingly transmitted cyclically during the transmission of a picture for synchronizing the receiver drum or drums for the picture.

In adjusting the transmitter, potentiometer 109 is suitably set for operating the photoelectric cell 105. The potentiometer 116 is adjusted so that the bias for the control grid 113 permits a small tone signal to be transmitted during the black elements of the picture. The frequency of the carrier may, for example, be 2000 cycles. In one embodiment, milliammeter 130 may indicate .1 of a millampere as the average direct current in the anode 122 circuit corresponding to black. A white picture element corresponds to the maximum value of transmitted carrier signal. The corresponding reading of the milliammeter 130 may be, for example, .8 of a milliammeter indicating an increased anode current.

Adjustments of the potentiometers 116 and 124 are made with black and white light signals impressed upon the photoelectric cell 105, giving corresponding meter 130 indications, in this example, of .1 and .8 milliammeters. Intermediate shading between black and white corresponds to transmitted tone or carrier signals of intermediate intensity, and the meter 130 will have corresponding intermediate indications. The adjustments are made so that the maximum transmitted signal corresponding to white picture elements should not exceed a predetermined value. In half tone reproduction it is not desirable to

have the maximum received signal, corresponding to white, too large, since the shading effect of the received picture will not be fully reproduced. It is preferable to have the maximum picture signal correspond to a light gray on the film at the receiver to insure all the variations between the maximum white signal and minimum black signal being reproduced.

A relatively small carrier output corresponding to black picture elements is preferably produced, to have the picture signals override any background or line noise or interference signals, although a zero carrier output may be used for "black". Although in my preferred telepicture system, the shading of a picture yields varying picture signal intensities, it is to be understood that black and white facsimile reproductions may be transmitted by such apparatus, the signals being represented by corresponding minimum and maximum carrier signal strengths.

Figure 12 is a plan view of a preferred embodiment of the telepicture transmitter apparatus schematically illustrated in Figure 11. The apparatus is mounted on a heavy cast iron base 150 if it is designed for non-portable use. Synchronous motor 107 drives the cylindrical drum 103 by suitable gearing contained in housing 151. Figure 13 is a cross sectional view along 13-13 of Figure 12 illustrating in detail the mechanical driving system for the transmitter drum 103. The motor shaft 152 is connected by a standard flexible coupling 153 to the pinion gear 154 which drives the worm gear 155. Shaft 156 connects the pinion 154 to the flexible coupling 153. The hub 155' of the worm gear 155 is rotatably mounted on shaft 157. Drum 103 is driven through the friction clutch 158. Worm gear hub 155' is keyed to inner member 159 of the friction clutch 158 by key 160. The coacting outer friction clutch member 161 is pinned at 162 to the shaft 157.

The clutch members 159 and 161 serve as a metal to metal friction clutch for driving the shaft 157. The clutch 158 is engaged and disengaged by means of the hand lever 164, the opposite end of which contains a forked member (not shown) coacting with a clutch 165 in clutch member 159 as is well known in the art. A spring 166 mechanically biases clutch member 159 into engaged position. Lever 164 moves member 159 against spring action, to the dotted disengaged position. A suitable holding mechanism is located within the pivot 167 of the lever. The face plate driver 170 is keyed to shaft 157 and is contained in bearing 171. The end 172 of the shaft 157 is conical and supports a corresponding cavity in the shaft 169 of the drum 103 set in the center of the cylinder end plate 173. A projection or key 174 on the driver plate 170 engages with a corresponding groove in the drum flange 173 to effect a positive driving connection between the friction clutch member 161 and the drum 103.

The drum 103 elements, including the end plates 173, and the peripheral plate 175 are preferably made of a light weight metal such as aluminum to minimize the rotational inertia of the drum. The shaft 169 is preferably hollow. The drum 103 of my preferred embodiment for a stationary telepicture transmitter has an eleven inch circumference and is seventeen inches long. It is made as strong and light in weight as is feasible. The friction clutch 158 is inserted between the synchronous motor 107 drive and the drum 103 to be driven, so that the drum may be

removed from or inserted into position without disconnecting the motor drive. The friction clutch is designed so as not to slip during normal operation of the mechanism. The friction clutch 158 permits the relatively large drum 103 to start up from rest while the synchronous motor 107 continues rotating.

The opposite end of the cylinder drum is supported in a spindle 176 having a conical point projecting into the corresponding end of shaft 10 169. The spindle 176 may be released from engagement with the drum 103 by means of operating the thumb screw 177 located at its end. The housing 178 contains the "tall stock" mechanism permitting the movement and locking of 15 spindle 176. Figure 28 which will be herein-after described in detail in connection with the receiver mechanism is a partial perspective illustration of this mechanism, for the receiver.

The synchronous motor 107 may, for example, 20 revolve 1800 revolutions per minute. The ratio of the worm and pinion 154-155 is designed to rotate the drum 103 at a predetermined rate, for example 100 revolutions per minute. Reduction gears 180 connect gear 181 mounted on shaft 157 25 to gear 182 attached to one end of the worm or feed screw 183 to rotate the worm 183 at a reduced rate. The worm 183 drives the carriage 184 housing the transmitter optical and electrical equipment parallel to the axis of the drum 103. 30

Figure 14 is a side elevation of Figure 12 viewed toward the left side. The motor 107 is shown mounted on a base 101' attached to the transmitter base 150. The reduction gearing 181- 35 182 is clearly illustrated.

A worm lock engages the worm 183 and is attached to an extension plate 185 of the carriage housing 184. Figure 30 is a cross sectional view through the worm lock mechanism. The worm lock comprises two similar members 186-187 40 operated by the cam lever 188 through pins 190-191. The worm lock 186-187 engages the worm 183 in a well known manner. The cam lever serves to engage or disengage the worm lock 186-187 upon the worm 183. Rotation of worm 183 advances the carriage 184 supported in V notched tracks 192 and 193, moving the transmitter carriage 184 parallel to the drum 103 at a predetermined rate. The feed corresponds to the width of one scanning line traversed in the 45 time required for one revolution of the drum 103. In the present embodiment, the carriage 184 is advanced one inch in one minute so that since the drum 103 is rotated 100 revolutions per minute, a line width of ".01" is had.

A rubber collar 194 is mounted in a metal collar 195 which is fixedly attached to the worm 183 as shown in Figure 12. The rubber collar 194 acts as a bumper or stop mechanism to define the extreme left position of the carriage 184. The threads at the opposite end 183' of the worm 183 shaft are omitted so that when the carriage is at the extreme right position there will be no propelling force tending to move it beyond the 55 end of the apparatus, as will be evident.

In Figure 12 I have illustrated V tracks coacting with V grooved rollers 196 to keep the movement of the carriage 184 precisely parallel to the axis of the drum. This arrangement 60 minimizes any tendency for undesirable transverse movement of the carriage 184. Since the transmitter optical system is sharply focused upon the picture mounted on the drum 103, and the proper adjustment of the optical system de- 75

pends upon the relative distance between the surface of the drum 103 and the carriage 184, it will be evident that the suppression of relative transverse movements is essential for eliminating distorting influences.

Figure 15 is a cross-sectional view along 15-15 of Figure 12 being a section through the track and roller wheel members which support and guide the transmitter carriage 184. The tracks 192 and 193 project upwardly, their sections forming an inverted V. Roller wheels 196 are correspondingly V grooved, formed to ride thereon.

A plurality of film clip members 206 are disposed along one section of the circumference of the picture drum 103 for engaging opposite ends of a picture sheet to be transmitted. Figure 16 is a cross-sectional illustration of the film clamping assembly 206 and the rollers 201. Figure 17 is a perspective illustration of a portion of the film clamping assembly 206. A film or picture sheet 202 is placed upon the picture drum 103 in the following manner:

The coacting film clamps 203 and 204 have two portions 205 and 206 for gripping the corresponding opposite ends 207 and 208 of the picture sheet 202. A cam 216 operates upon each film clamping assembly 206. The cam members 216 are mounted on a common cam shaft 218 at one end of which is attached a lever 212. The coacting film clamps 203-204 are riveted together at their pivot 211. The ends 215 and 216 of the clamps 203-204 are elastically fastened by spring 216. The normal position of the clamps 203-204 is such that their toothed portions 205 and 206 grip against the surface plate 115 of the drum 103, or grip into the corresponding ends 207 and 208 of the picture sheet 202. It is to be understood that the clamping mechanism 206 illustrated in Figure 16 is duplicated in the plurality of clamping members 206 illustrated on the drum 103 in Figure 12.

For inserting one end 207 of the record sheet 202 under the toothed portions 205 of the film clamp 203, the lever 212 is moved so that the cam 216 presses against the arm of the film clamp 203. The toothed portion 205 of clamp 203 is accordingly raised from the drum surface 115 permitting the edge 207 of sheet 202 to be inserted thereunder. It is to be understood that this edge 207 is inserted under corresponding toothed portions 205 of clamping mechanism 206. The lever 212 is returned to its normal position, and the clamp teeth 205 grip the edge 207 of the sheet 202 firmly to the drum surface 115.

The rollers 201 are moved into engagement with the drum 103 as is illustrated in Figure 15. The drums 201 exert sufficient pressure upon the film 202 along the drum 103. The plurality of rollers 201 are illustrated pressing upon the drum in Figure 12. The dotted section 201' indicates the position of rollers 201 out of operative relation with drum 103. The rollers are preferably solid metal cylinders rotatably mounted on a common shaft 220 with spacing washers 221 separating them. The distance between the rollers 201 corresponds to the width of the projecting clamping members 206 so that no interference between them is had. A rubber or other suitable surfacing 222 is placed on the rollers 201 to protect the film or record sheet 202 which is rolled upon.

Figure 16 illustrates how the rollers 201 are used to facilitate proper mounting of the record 202 upon the drum 103. After one end 207 of the sheet 202 is gripped into position by clamp members 206, the rollers 201 are pressed down near

the end 207 and the drum 103 is slowly rotated manually. The film 202 is accordingly firmly pressed in position around the drum 103 and the opposite end 208 is gripped under the teeth 206 of clamps 206 by operation of the lever 212 and cam members 216 as will be understood.

The film clamping arrangement according to my invention provides for gripping any length of picture to be transmitted. The drum has a circumference of eleven inches, and in my preferred embodiment is seventeen inches long. Standard 10" x 14" pictures are readily accommodated on such a drum. Pictures of different sizes may be transmitted on the drum 103. The only requirement is that one dimension of the sheet 202 should be such as to fit onto the drum 103 to be securely clamped in position by the clamping mechanism 206. The rollers 201 assist in smoothly mounting the picture sheets 202. I also provide a scale 238 which is marked along the "dead" or underlap portion of the drum, namely that portion containing the clamping members 206 for the "dead" ends of the picture sheet. Small circumferential grooves 231 are made in the surface 115 of the drum 103 corresponding to the integral marked spacings of the scale 238. The distance between these grooves or scale markings is preferably integral, such as one inch. The operator is accordingly exactly apprised of either the length of the picture to be transmitted or of the length of a picture already scanned during its transmission.

Figure 12 shows the plan view of the transmitter carriage 184 with the coverplate removed. The transmitter carriage 184 houses the optical and electrical transmitter assembly corresponding to the schematic representation thereof in Figure 11. The light source 186 is mounted on a projection 240 of the housing 184 and comprises a 50 watt lamp having a filament 187 in a plane parallel to the focusing lens system 182. A hole 248 is made in the housing 184 between the filament 187 and the focusing system 182. Figure 15 illustrates a sectional elevation through the transmitter assembly, and the relative position of the filament 187, hole 248 and the lens system 182. The light beam 181 is directed to a single point 242 upon the picture mounted on the drum 103.

The lens system 182 reduces the diameter of the light source 186 to a circular point .01" in diameter. It is to be understood that the telepicture transmitter 1 is operated in a photographically darkened room so that no extraneous light affects the transmission of the picture. The intense light point 242 is refracted from the picture element which impinges along beam 104 and is collected and focused by the lens system 182 to the photoelectric cell 105 housed in a light proof casing 243. The end 244 of the lens system 182' assembly projects into a corresponding opening in the photocell housing 243 to retain the light proofing of the housing for the photocell and to permit the impression of the refracted beam upon the photoelectrical cell 105 through 60 the lens system 182'.

Micrometer adjustments are preferably attached to the lens system 182 and 182' to facilitate accurate focusing and adjusting of the optical system. Such attachments are well known in the art, and I have not illustrated them. A simple microscope may also be mounted upon a carriage 184 adjacent to the optical system, and focused upon the light point 242 on the picture. I have not illustrated such a microscope or view-

ing means, but it is to be understood that such a device is helpful to the operator for viewing the adjustment of the optical light source as projected upon the picture at point 242. The optical point 242 is adjusted sharply to ".01" in diameter, as already explained. A cross line calibrated scale is preferably mounted in the microscope viewing means for appraising the operator of the exact diameter of the light point 242.

10 The screen grid tube 114, triode 128, milliammeter 130, potentiometer 116 and impedance chokes 121 and 123 are indicated in the plan view of Figure 12. A flexible cable 245 connects the transmitter assembly 184 to the voltage sources as indicated in schematic Figure 11, and also contains the leads 3-4 connecting the secondary of the output transformer 133 to the audio amplifier 2 (Figure 1), as well as the tone generator 1a leads from the potentiometers 124 and 125.

15 The synchronizing cam 135 is shown in detail in Figure 12A. Cam switch blade 136 is operated by the projection 131 for intermittently closing the circuit at contact 138 in the synchronizing circuit leads 139 and 140 corresponding to the 20 schematic illustration thereof in Figure 11. The cam 135 is mounted at the left end of the shaft 157 and is rotated by the shaft 151.

25 The angular position of the cam projection 131 corresponds to the position of the underlap portion 30 of the drum 103 containing the clamping members as illustrated in Figures 13 and 14. A bracket 246 supports the cam switch 136-138 to the housing 151 as illustrated in Figure 14.

Telepicture receiver

30 Figure 18 is a schematic electrical diagram of the telepicture receiver of my present invention and corresponds to translator 11 of Figure 1. The telepicture signals from the transmitter 1 are transmitted over any one of the channels indicated in Figure 1, and received at the receiving station. The telepicture signals corresponding to the modulated audio frequency carrier are introduced to the audio amplifier 10 for suitable amplification thereof. The output of amplifier 10 is connected by leads 14-15 to the input stage of a push-pull class B amplifier 300, through the interstage transformer 301. The push-pull stage 300 comprises two amplifier tubes 302 and 303 40 connected in a well known manner. The output of the push-pull stage 300 is connected to the primary 304 of the output transformer 305. The output of the secondary 306 of transformer 305 is connected to a photolamp 307 containing a gas 45 such as neon, for producing a light beam 307a output in accordance with the telepicture signals received. The light output 307a from lamp 307 is suitably focused upon the receiving drum 308 by a lens system 309.

50 I prefer to use a neon crater photo-lamp 307 having a control electrode 310 which is connected to one terminal 311 of the transformer secondary 306 and an auxiliary or striking electrode 317. The plate 312 of lamp 307 is connected to the positive terminal of a suitable direct current source 313, the negative terminal of which is connected to ground. The other terminal 314 of the transformer secondary 306 is connected to the plate 312 through a variable resistance 315 and fixed resistance 316. The auxiliary or striking electrode 317 is connected to ground by lead 318. As is well known in the art, the auxiliary electrode 317 maintains a striking or discharge condition at the photo-lamp plate 312, so that it will 55 always be in readiness to respond to telepicture

signals introduced between the plate 312 and the control grid 310. A by-pass condenser 319 is connected between the output terminal 314 and ground.

5 The receiver drum 308 is driven by a synchronous motor 320 connected to supply lines 108. The lines 108 are preferably from the same alternating current supply as those of the transmitter 108 although such condition is not essential. The synchronous motor 320 drives drum 308 10 through the schematically indicated overrunning or positive clutch 321. The details of the drive mechanism of my present invention will be set forth hereinafter. Drum 308 is preferably driven at a slightly faster speed than the corresponding 15 transmitter drum 103, for example, in a ratio of 101:100. The clutch 321 is under control of armature 322 which is actuated by the synchronizing magnet 323, to maintain the drum 308 in phase synchronism with the transmitter drum 20 103 as will be hereinafter set forth. A direct current potential source 324 supplies the magnet 323 through the relay contacts 325-326.

25 The anode potential source 327 for the push-pull amplifier stage 300 is supplied to the center tap 328 of the primary 304 through the synchronizing cam switch 330-331. A cam 332 is connected to the shaft 333 at the driven side of the overrunning clutch 321. The projection 334 of the cam 332 is the same angular position on shaft 333 30 as the film clamping members 335 of the drum 308 corresponding to the underlap or "dead" portion of the drum. The cam switch 330-331 is normally maintained closed during the major portion of the rotation of cam 332, and the anode 35 current normally flows to the push-pull amplifier stage 300 during the reception of the telepicture signals.

40 The cam switch 330-331 is opened by the projection 334 of the cam 332 during the synchronization or underlap period of the receiver. The anode current from source 327 is accordingly directed to the amplifier 300 through the synchronizing relay 336, which relay 336 is otherwise short circuited by switch 330-331. The synchronizing signal, as hereinabove described, occurs during the underlap period of the picture transmitter, and is preferably of greater magnitude than the telepicture signals. Synchronizing relay 336 is preferably a marginal relay responding 45 only to the increased magnitude signals so as to avoid the possibility of interference of the synchronizing action by any of the telepicture signals. The push-pull amplifier 300 rectifies the synchronizing tone impulse in the anode lead, 50 and the actuation of the relay 336 is by rectified or unidirectional current as will be understood by those skilled in the art.

55 Although I prefer to use synchronizing signals of increased intensity, and a marginal synchronizing relay, I have also successfully employed synchronizing signals of intensity equal to the "white" picture element signals operating an ordinary relay. It is also to be understood that the synchronizing magnet 323 may be directly energized by the synchronizing signals, displacing the relay 336. However, in large receivers it is preferable to use a relay since local energization of the magnet permits the design of a more powerful clutch control mechanism.

70 The receiver drum 308 is prepared for the synchronizing signal during the receiver drum 308 underlap period. The synchronizing signal will accordingly flow through and energize the synchronizing relay 336 which then closes the 75

relay contacts 325—326, locally energizing the synchronizing magnet 323. The synchronizing magnet 323, when energized, will attract the clutch trip armature 322 to permit the overrunning clutch 321 to continue to drive the receiver drum 308; i. e., if the drum 308 were in synchronism and in proper phase, the release of armature 322 from the clutch would permit the drum 308 to continue to rotate in phase. The 10 drum 308 of the preferred embodiment of my invention rotates slightly faster than the transmitter drum and the overrunning clutch 321 is accordingly momentarily tripped due to action of the armature 322 normally mechanically biased to tripping position. The synchronizing relay 336 actuates the synchronizing magnet 323 to cyclically attract the armature 322 away from the clutch 321 to maintain the scanning lines of the received picture in phase with respect to 15 each other and the transmitter.

Figure 19 is a plan view of a preferred embodiment of a telepicture receiver according to my invention. This receiver corresponds to the translator 11 of the telecommunications system 25 illustrated in Figure 1. The mechanical construction of the receiver is similar to that of the corresponding transmitter described in connection with Figures 12 to 17. The telepicture receiver, however, has several modifications necessary to translate the received picture signals into corresponding varying light impulses upon a picture film.

The receiver is mounted on a cast iron base 350. Synchronous motor 328 drives the receiver drum 308 through the overrunning clutch 321. The receiving drum 308 contains the film clamps 335 which are similar in construction to the clamps 208 described hereinabove. The rollers 351 are similar to the rollers 201 of the transmitter, and are used for smoothly mounting the film upon the drum 308.

Figure 21 is the cross sectional view along 21—21 of Figure 19 through the axis of the drum 308, illustrating in detail the method for driving and mounting the drum 308. The shaft 352 driven by the motor 328 through the flexible coupling 353 contains the worm 354 which drives the worm gear 355. The hub 356 of the worm gear 355 is connected to the clutch driver 357 by projections 358 of the hub 356 into corresponding grooves in the clutch driver 357. The worm gear 355 and the clutch driver 357 are free to rotate upon the spindle 360. A housing 361 encloses the worm and pinion drive and contains the bearing 362 which supports one end of the spindle 360.

Figure 26 is a perspective illustration of the disassembled overrunning clutch to more clearly show its operation. The clutch cam plate 363 is rotatably mounted upon the spindle 360 within the clutch driver 357. There are four openings 364 on the surface of the clutch containing metal cylindrical rollers 365. The clutch stop plate 366 is fitted adjacent to the cam plate 363 and contains four pins 367 which coact with the cylindrical rollers 365.

Figure 22 is a sectional view through the overrunning clutch 321 illustrating the character of the recesses 364 in the cam plate. The principle of the operation of an overrunning clutch is well known in the art. The rollers 365 are wedged between the inner surface 370 of the clutch driver 357 and the inclined surfaces 371 of the recesses 364. The plungers 372 are forced 75 against the rollers 365 by springs 373 set within

the cam plate 363. The wedging action of the rollers 365 serves as a positive connection between the clutch driver 357 and the cam plate or clutch driven member 363.

The cam plate has a V notch 374 at one end 5 of its hub 375, which coacts with a V projection 375 in the coupling member 376. Coupling member 376 has key ways 377 that slidably engage corresponding key 378 attached to the spindle 360. It is to be understood that the 10 coupling member 376 is axially slideable on the spindle 360 and that the coupling member 376 drives the spindle 360, since no circumferential movement between the two is permitted. Although I have illustrated a slideable keyway construction, a splined spindle 360 may be used.

Accordingly when the overrunning clutch 321 is engaged, the motor drive 328 is transmitted by the worm and pinion 355—352, the clutch 321 and the coupling member 376 to the spindle 360. 20 The face plate driver 380 is rigidly connected to the spindle 360 by pin 381. A projection or key 382, on the face 383 of the driver 380 sets into a corresponding groove in the end-plate 384 of the receiver drum 308. The hollow shaft 385 25 of the drum 308 contains a conical groove to fit onto the conical or pointed end 386 of the spindle 360. A positive driving connection is accordingly had between the motor 328 and the receiver drum 308 when the positive or over- 30 running clutch 321 is engaged.

A set of pins 387 project from the opposite end of the face plate driver 380 to press the coupling member 376 into engagement with the V notches 374 of the cam 363. Springs 388 press 35 the pins 387 against the face of the coupling member 376. The opposite end of the drum 308 has a flange 390 which contains the corresponding insert of the hollow drum shaft 385. A supporting member 391 having a conical or pointed end 392 projects into the shaft 385, which contains a corresponding cavity. The drum 308 is accordingly rotatably supported by point 392. 40

Figure 28 is a partial perspective illustration of the tail-stock arrangement for the drum 308. 45 The support 393 contains the bearing 394 for the member 391 and rod 395. A spring 396 mechanically biases the member 391 outwardly from the rod 395 pressing the member 391 against the drum 308. A thumb screw 397 is mounted 50 on the end of rod 395 for manual engagement and disengagement of the member 391 from the drum 308. A pin 398 projects through rod 395. The opposite ends 399—399 of the pin 398 move in corresponding longitudinal oppositely disposed slots 400 in member 391. A further pin 401 projects from the rod 395 into a slot 402 in the tail stock support 393. The slot 402 guides pin 401 to the locked position 403 when the thumb screw 397 is pressed toward the drum 60 and simultaneously twisted. The locked position 403 for the pin 401 holds the rod 395 against the spring 396 pressing the member 391 against the drum 308. To disengage the member 391 from drum 308, the thumb screw 397 is reversed- 65 ly twisted and simultaneously pulled outwardly along groove 402 to the dotted position illustrated in Figure 28. Member 391 is accordingly disengaged from drum 308. The drum may therefore readily be removed from its mounting. 70

An important feature of my present invention resides in the automatic connection and disconnection of the positive or overrunning clutch 321 to maintain the revolving receiver drum 308 in phase synchronism with the transmitter drum 75

103. In my Reissue Patent No. 19,575 is described one method for connecting and disconnecting the positive drive from between the source of motive power and the revolving drum. My present invention embodies the principle of the overrunning clutch in an instantaneous synchronization mechanism. Synchronization according to my Reissue Patent No. 19,575 depends upon the actuation of a pawl engaging a ratchet wheel in the positive driving connection. The limits of phasing positions is accordingly within the pitch or width of one tooth of the ratchet wheel.

By employing an overrunning clutch, the positive drive is had during the rotation of the drum 308 and accurate phase synchronization is feasible at any point in the circumferential movement of the drum. The stop plate 366 contains the pins 367 which coact with the wedging rollers 365. When the cam plate 363 is driven by the clutch driver 357 during the wedging action of the rollers 365, the stop plate is also driven and revolves with the cam plate. However, I provide a notch 404 on the periphery of the stop plate 366 which is engageable with a projection 405 on trigger lever 406 which is mechanically biased by spring 407 toward the stop plate 366.

Figure 23 illustrates the engagement of lever projection 405 with the corresponding notch 404 in the stop plate 366. In this position the stop plate is prevented from further rotating counterclockwise, as indicated by the arrow. The pins 367 accordingly abut the rollers 365 within the overrunning clutch and force the rollers 365 against the plungers 372 to disengage the clutch 321, as will be understood by those skilled in the art. The rollers 365 are moved along the inclined surfaces 371 releasing the wedging action of the rollers 365 from between the cam plate 363 and the inner clutch driver surface 370. The motor 320 continues to rotate the clutch driver 357 but the driving of the drum 308 therefore is discontinued.

Figure 27 is a cross sectional detailed view illustrating the arrangement of a roller 365 and pin 367 within the recesses 364 of the cam plate and in engaged position, where the plunger 372 is pressed against the roller 365 by spring 373 set in the cam plate 363.

A pawl 410 is mechanically biased toward the stop plate by spring 411. Pawl 410 projects into a notch 412 on the periphery of stop plate 366 at the instant the projection 405 of the trigger lever 406 engages the notch 404 in the stop plate 366. The pawl 410 accordingly prevents rebound 55 of the stop plate when its notch is arrested, thus insuring a positive disengagement of the overrunning clutch 321.

For rapid engagement of the overrunning clutch in response to synchronizing signals, falling weight 413 is caused to impact the end 414 of the trigger lever 406, removing the projection 405 from the notch 404 in the stop plate 363 and permitting the plungers 372 to wedge the rollers 365 between the cam 363 and the clutch driver 357. The movement of weight 413 is guided by post 415 through a hole in the center of the weight 413.

Figure 23 illustrates the weight 413 in its upper position. A projection 416 on the armature 322 of the synchronizing magnet 323 holds the weight 413 in its upper position in readiness for release. When a synchronizing impulse is impressed upon magnet 323 in a manner hereinabove described in connection with schematic Figure 19, the armature 416 is attracted toward the magnet 323

against the spring 417 permitting the weight 413 to drop and impact the end 414 of trigger lever 406 to drivingly engage the clutch 321 as illustrated in Figure 24.

The weight 413 is replaced to its upper position by means of the lever 420. A pin 421 projects from the surface of the stop plate 326 and once per revolution of the stop plate, the pin 421 presses the end 422 of lever 420 downward so that the opposite end 423 automatically raises 10 the weight 413 to its upper position shown dotted in Figure 24. Spring 417 moves the armature 322 away from the magnet 323 permitting the projection 416 to engage the bottom corner of the weight 413 to hold it in its upper position 15 in readiness for its cyclical release. Figure 25 is a sectional view along 25-25 of Figure 21 showing the driving connections from the motor coupling 353 and is a plan view of the synchronizing levers 406 and 420, weight 413 and magnet 323.

The receiver drum 308 is accordingly maintained in phase synchronism by means of the cyclically transmitted synchronizing signals during the underlap period of the drum. The receiver synchronizing cam 332 is mounted at the end of the spindle 360 outside the housing 361 clearly illustrated in Figure 21. The subtended angle of the cam nib 334 may be made equal to the corresponding subtended angle of the underlap portion of the receiver drum 308 so that the receiver synchronizing switch 330-331 will be maintained open during this interval so that the synchronizing relay 336 will be connected in the circuit of the amplifier 300 output as illustrated 35 in Figure 19.

It is to be understood that since the amplifier 300 is a class B amplifier the tubes are biased to "cut off", so that when no signal is impressed in the input circuit, zero plate current will flow 40 and the synchronizing magnet 336 will not be energized until the synchronizing impulse is impressed. In my preferred embodiment, the synchronizing impulse is of a magnitude greater than the largest telepicture signal so that the relay 336 will respond only to the synchronizing signals. The relay 336 receives rectified or direct current since the push-pull arrangement rectifies the alternating current signal in its anode 45 supply lead as is well known.

Relay 336 is preferably a marginal relay responding only to the increased synchronizing signal amplitudes to avoid interference of the synchronizing action by any of the picture signals. The synchronizing switch 330-331 is supported on housing 361 by bracket 425. It is to be understood that an ordinary synchronization relay responding to maximum instead of increased synchronization signals may be employed.

The parts of the receiver drum 308 are preferably made of aluminum to reduce its rotational inertia. The coupling member 376 coacting with the driven cam plate 363 of the overrunning clutch 321 acts as a shock absorber to resist the inertial resistance of the drum 308 during its 60 starting from rest to synchronous speed, or of any inertial forces it may present during the synchronizing action.

When there is a tendency for the cam plate 363 to advance in phase with respect to the coupling member 376, the coupling member will slide axially along the spindle 360 away from the clutch cam 363 and against the pressure of the pins 387 mechanically biased by springs 388. The V notches 374 of the cam hub 369, coacting with 75

the V projections 375 of the coupling member 376, effects a positive driving action between the two when they are in engagement. A relative motion between the cam 366 and member 376 causes its V projection to slide away from the V notches 374 proportional to the forces tending to resist their in-phase movement. Such forces occur momentarily, and the coupling member is again forced into normal engagement with the V notches 374 by the pins 381.

Any momentary relative movement between the clutch driven member 363 and the member 376 is automatically compensated by the return of the V projections 375 into normal engagement with the V notches 374. A spring 430 connects an eyelet pin 431 secured in the coupling member 376 and another eyelet pin 432 secured in the hub 369 of the cam plate 363, as illustrated in Figures 23 and 24. Spring 430 facilitates the automatic return engagement of the V projection 375 in the V notches 374 of the corresponding members.

Since the coupling member 376 is slidably keyed or splined to the spindle 360 and the face plate 25 driver is rigidly keyed to the spindle 360, the receiver drum 308 is driven positively from the coupling member 376. The source of motive power 320 is connected positively to the clutch driver 357 as already described. When the clutch 321 30 is engaged, a further positive connection is had between the clutch driver 357 and the cam 363, by the wedging action of the rollers 365. The V connection between the hub 369 of cam 363 and the coupling member 376 is in effect a flexible 35 positive coupling.

When the projections 375 normally engage notches 374, the source of motive power 320 drives the receiver drum 308 through a positive driving connection. The relation of the hub 374 and coupling member 376 as already described is a flexible positive connection since it permits momentary changes in phase, but automatically returns to the normal phase relation. The synchronizing apparatus operating on the clutch stop 45 plate 366 disconnects the positive driving connection between the source of motive power 320 and the receiving drum 308 at the positive or overrunning clutch 321 if the receiver drum 308 is not in phase synchronism with the transmitter.

50 The worm or feed screw 450 is driven from the gear 451 connected to the spindle 360 by means of the reduction gearing 452. The receiver carriage 453 is arranged on V tracks 454—454 and V rollers 456 similar to the transmitter carriage 184. A worm lock operated by cam lever 457 is used to engage the carriage and the worm 450. Details of the worm lock have been hereinabove described for the transmitter in connection with Figure 30.

60 Figure 20 is a cross sectional view through the receiver carriage 453 and the receiver drum 308. The film clamps 335 and film rollers 351 are similar to corresponding parts of the transmitter and need not again be described in detail. The receiver carriage houses the signal lamp 307 within a threaded casing 460. The threaded casing 460 is vertically adjustable within the threaded sleeve 461 for accurate manual adjustment of the distance between the signal lamp 307 and the ninety degree reflecting prism 462. The light beam 463 emitted from the photo-lamp 307 is reflected by prism 462 along beam 464 at right angles thereto, through the focusing lens system 309 upon the film mounted on the receiver drum 308 at point 75 465.

It is to be understood that the receiver drum 308 rotates in synchronism and in phase with the corresponding transmitter drum 103, and that the carriage 453 simultaneously advances the impinging signal light beam 464 axially along the film mounted on the drum 308 to record the picture being transmitted. The intensity of the light beam 464 sharply focused upon the point 465 on the film varies in accordance with the shading of the picture being transmitted as is evident to those skilled in the art.

In my preferred embodiment a positive picture is transmitted and a telepicture signal of increased intensity results from a white picture element being transmitted. The impinging light beam 464 is of correspondingly increased intensity to expose a picture element which will record as a white picture element when the film is developed. A positive film thus used at the receiving station will produce a telepicture reproduction when developed. The amplifier stages for the receiver are preferably not placed in the carriage 453 and are electrically connected to the carriage by means of the flexible cable 470.

It is to be understood that although I illustrate the reproduction of a positive picture directly from the received telepicture signals, I may arrange the receiving circuit so that a negative reproduction of the picture will result. One method for reversing of "positive" telepicture signals to "negative" translation thereof is to positively bias the control grid of the demodulation stage so that a relative inversion of the telepicture signals results as is well known by those skilled in the art. It is also to be understood that although I have illustrated the tone modulated telepicture signals as being directly impressed upon the signal lamp for telepicture reproduction that the tone or audio frequency carrier component of the telepicture signals may be in turn removed or demodulated to produce the original picture shading variations generated in accordance with the shading of the transmitted picture. The rectified picture signals are then either directly impressed upon the signal crater lamp or are first amplified by a direct current amplifier.

To preserve the quality and uniform predetermined shading of a reproduced picture, it is important to maintain the characteristics of the transmission channel constant with respect to amplitude. I accordingly provide automatic volume control circuits for the receiving amplifier stages to maintain the reception level constant to in turn preserve the relative shading intensities of the reproduced pictures as will be understood. Although for simplicity, I have not illustrated one of the well known automatic signal level control circuits, it is to be used in conjunction with the receiver whenever the characteristic of the transmission channel is subject to amplitude variations.

A modification of the synchronizing magnet-clutch trigger arrangement is illustrated in Fig. 32, corresponding to Fig. 23. The synchronizing magnet 323 is mounted on a bracket 480 below the surface 481 of the base 350. The poles 482 of the synchronizing magnet 323 projects through the surface 481 to coat with the armature plate 483 attached to the end 414 of the trigger lever 406.

Figure 33 is a cross-sectional view through the magnet 323 illustrating how the armature plate 483 is arranged above the two poles 482—482 of the electromagnet 323 and how the trigger end 414 is positioned between the poles 482—482. The 75

trigger 406 is accordingly directly actuated by the synchronizing magnet 323 without the use of a falling weight 413 as in the hereinabove described modification. While the clutch 321 and stop-plate 366 are rotating, the lever 401 will be held in the dotted position of Fig. 32 so that the armature plate 483 will be close to the poles 482 of the magnet 323. The peripheral surface of the stop-plate 366 will abut the trigger projection 405 and 5 press the lever 406 toward the poles 482 against the action of the biasing spring 407. The armature 483 will accordingly be close to the poles 482 of the magnet 323 during the major portion of the 10 revolution of the stop-plate 366, but will tend to be moved away under the action of spring 407 when the notch 404 comes in engaging position 15 with the projection 405 of the trigger 406.

If the drum 308 is in phase synchronism, the 20 synchronizing members will arrive at the synchronizing magnet 323 in time to hold the trigger 406 away from engagement with the stop-plate notch 404 and permit the drum 308 to continue in phase synchronism. It is to be understood that if the drum 308 is out of phase synchronism, the 25 notch 404 will engage the trigger projection 405 to disengage the positive or overrunning clutch. When the synchronizing signal is received by the magnet 323 the stop-plate is released and the clutch reengages to rotate the drum in proper 30 phase synchronism.

A modification for the slide supporting arrangement for the carriage assembly of the telepicture receiver or transmitter to substantially eliminate transverse vibration is illustrated by 35 Figs. 34 and 35. Figures 34 and 35 are respectively plan and side views of the receiver carriage 453. It is to be understood that although I illustrate the supporting mechanism modification in connection with the receiver carriage 453 that 40 it also may be used for the corresponding transmitter carriage 184.

The carriage 453 is mounted on a base plate 490 having V projections 491 and 492 on opposite sides thereof. Corresponding supporting 45 guide bars 493 and 494 contain V grooves for guiding and supporting the V projections 491-492 of the base plate 490. Guide bar 494 is fixedly mounted to the base 150 of the apparatus by screw members 495. Guide bar 493 is positioned parallel 50 to the drum 308 as is understood. Guide bar 493 is arranged parallel to bar 494.

The distance between bars 493 and 494 is adjustable to provide for accurate setting of the guiding arrangement for the carriage base plate 55 490, and to also provide for adjustment when wear or other forms of mis-alignment occur. Guide bar 493 is fastened on channel 496 by screw members 497. Slots 498 in bar 494 permit relative transverse adjustment of the bar 493 with 60 respect to the fastening screws 497. A plurality of set screws 500 are arranged on the upright side 498 of channel 496. Accurate transverse adjustment of guide bar 493 is had all along its length corresponding to the travel of carriage 453 as 65 driven by worm 450.

The worm 450 drive feeds the carriage at a relatively slow rate, for example, one inch per minute, and exerts a powerful propelling force so as to render any friction at the coacting V slide 70 members negligible. Accurate parallel adjustment of the guide bars 493-494 compels the carriage 453 to move along the accurately guided direction which is parallel to the axis of the drum 308. Any tendency for transverse vibrations of 75 the carriage 453 with respect to the drum 308 is

substantially eliminated, thereby providing undistorted mechanical scanning of the picture.

Although I have described in detail preferred forms of a telepicture transmitter and receiver, together with preferred arrangements for transmitting the picture signals or other telecommunications signals over a telephone line without physical interconnection thereto, or over portable radio transmitters for reception and re-radiation by more powerful radio stations, modifications 10 falling within the spirit and scope of my invention will be evident to those skilled in the art, and I therefore do not intend to be limited except as set forth in the following claims.

I claim:

1. In combination, a telephone line having a subscriber station including a phone-box unit at opposite ends thereof; an induction coil in each phone-box unit connected in said line at each of said stations; a transmitter for generating a carrier wave modified by signals; inductance means coaxial with one of said induction coils for electrically inducing said generated signals into said line when said stations are in operative connection; means coupled with the other of said inductive coils for picking-up said signals; and a receiver connected to said last mentioned means to be operated by said picked-up signals.

2. In a telepicture system, a telephone line having a subscriber station including a phone- 30 box unit at each end thereof, means at one end of said line for generating a carrier wave modulated by picture signals corresponding to the shading of a picture to be transmitted, means for generating an electrical field to electrically 35 induce said signals into said telephone line at said phone-box unit, and means at the other end of said telephone line for picking up said picture signals, and means between the said first and last mentioned means for providing a linear 40 frequency response transmission characteristic.

3. In a telepicture system, a telephone line having a subscriber station including a phone-box unit at each end thereof, means at one end of said line for generating a carrier wave modulated by picture signals corresponding to the shading of a picture to be transmitted, means for inductively inducing said signals into said telephone line at said phone-box unit and means at the other end of said telephone line for picking up said picture signals, and means between the said first and last mentioned means for providing a linear frequency response transmission 50 characteristic.

4. In a system for transmitting electrical signals over a telephone line having a subscriber station with a phone box and telephone receiver at each end thereof, means at one end of said line for generating a carrier wave modulated by signals to be transmitted; and means comprising a solenoid mountable on said phone box and controlled by said signal-modulated carrier wave for generating an electrical field to electrically induce corresponding signals into one end of said telephone line, said last means being 65 effective for inducing said signals only when the telephone receiver is moved to close the telephone circuit, and means for adjusting said solenoid for maximum efficiency in inducing said signals.

5. In a system for transmitting electrical signals over a telephone line having a subscriber station with a phone box, means for generating a carrier wave modulated by signals to be transmitted; means comprising a solenoid secured to 75

- said box controlled by said signal-modulated carrier wave for generating an electrical field to electrically induce corresponding signals into one end of said telephone line; means for adjusting 5 said solenoid for maximum efficiency, and a receiving station associated with the other end of said telephone line for receiving and translating said signals.
6. In a system for signalling over a telephone line having a subscriber station with a phone-box unit at each end thereof, means for generating a carrier wave modulated by signals to be transmitted; means controlled by said signal-modulated carrier wave for electromagnetically 10 inducing corresponding signals into one end of said telephone line at said phone-box unit; means between said first and last mentioned means for imparting a linear transmission frequency characteristic to said telephone line comprising a compensation network; and a receiving station coupled with the other end of said telephone line for receiving and translating said signals.
7. In a system for transmitting audio-frequency signals over a telephone line having a subscriber station with a phone-box, a source of carrier current, means for generating signals to be transmitted and modulating said carrier current; means comprising a solenoid controlled 15 by said signals for electrically inducing corresponding signals into one end of said telephone line at said phone-box; means comprising a compensating network between said first and last mentioned means for providing a linear transmission frequency characteristic to said line; and a receiving station coupled with the other end of said telephone line having means for picking-up said transmitted signals comprising a solenoid.
8. In a system for transmitting picture signals over a telephone line having a subscriber station with a phone-box at each end thereof and an induction coil in each phone-box, means for generating an audio-frequency carrier wave 20 modulated by signals to be transmitted; means controlled by said signals for electromagnetically inducing corresponding signals into one end of said telephone line comprising a solenoid cooperable with the induction coil at said first end of the telephone line; a receiving station coupled with the other end of said telephone line having means for picking-up said induced picture signals cooperable with the induction coil at said second end of the telephone line; and means between said first and last mentioned means for compensating the transmission frequency characteristic.

said box controlled by said signal-modulated carrier wave for generating an electrical field to electrically induce corresponding signals into one end of said telephone line; means for adjusting 5 said solenoid for maximum efficiency, and a receiving station associated with the other end of said telephone line for receiving and translating said signals.

6. In a system for signalling over a telephone line having a subscriber station with a phone-box unit at each end thereof, means for generating a carrier wave modulated by signals to be transmitted; means controlled by said signal-modulated carrier wave for electromagnetically 10 inducing corresponding signals into one end of said telephone line at said phone-box unit; means between said first and last mentioned means for imparting a linear transmission frequency characteristic to said telephone line comprising a compensation network; and a receiving station coupled with the other end of said telephone line for receiving and translating said signals.

7. In a system for transmitting audio-frequency signals over a telephone line having a subscriber station with a phone-box, a source of carrier current, means for generating signals to be transmitted and modulating said carrier current; means comprising a solenoid controlled 15 by said signals for electrically inducing corresponding signals into one end of said telephone line at said phone-box; means comprising a compensating network between said first and last mentioned means for providing a linear transmission frequency characteristic to said line; and a receiving station coupled with the other end of said telephone line having means for picking-up said transmitted signals comprising a solenoid.

8. In a system for transmitting picture signals over a telephone line having a subscriber station with a phone-box at each end thereof and an induction coil in each phone-box, means for generating an audio-frequency carrier wave 20 modulated by signals to be transmitted; means controlled by said signals for electromagnetically inducing corresponding signals into one end of said telephone line comprising a solenoid cooperable with the induction coil at said first end of the telephone line; a receiving station coupled with the other end of said telephone line having means for picking-up said induced picture signals cooperable with the induction coil at said second end of the telephone line; and means between 25 said first and last mentioned means for com-

pensating the transmission frequency characteristic.

9. In a system for transmitting facsimile signals over a telephone line having a subscriber station with a phone-box at each end thereof and an induction coil in each phone-box, means for generating a carrier wave modulated by signals to be transmitted; means controlled by 5 said signal-modulated carrier wave for electromagnetically inducing corresponding signals into one end of said telephone line comprising a solenoid placeable on the phone-box at said first end of the telephone line and coaxial with its induction coil.

10. In a system for transmitting picture signals over a telephone line having a subscriber station with a phone-box at each end thereof and an induction coil in each phone-box, a source of audio-frequency carrier current, means for generating signals in accordance with the shading of a picture to be transmitted and for modulating said audio-frequency current; means controlled by said signals for electrically inducing corresponding signals into one end of said telephone line comprising a solenoid cooperable 20 with the induction coil at said first end of the telephone line; a receiving station coupled with the other end of said telephone line having means for receiving said picture signals and means for translating said signals.

11. In a system for transmitting picture signals over a telephone line having a subscriber station with a phone-box at each end thereof and an induction coil in each phone-box, a source of audio-frequency carrier current, means for generating signals in accordance with the shading of a picture to be transmitted and for modulating said audio-frequency current; means controlled by said signals for electrically inducing corresponding signals into one end of 25 said telephone line comprising a solenoid cooperable with the induction coil at said first end of the telephone line; a receiving station coupled with the other end of said telephone line having means for picking-up said induced picture signals cooperable with the induction coil at said second end of the telephone line; and means between said first and last mentioned means for compensating the transmission frequency characteristic.

50 WILLIAM G. H. FINCH.

DISCLAIMER

2,047,863.—William G. H. Finch, New York, N. Y., TELECOMMUNICATIONS SYSTEM. Patent dated July 14, 1936. Disclaimer filed September 3, 1941, by the assignee, Finch Telecommunications, Inc.

Hereby enters this disclaimer to claims 1, 4, 5, and 9 of said patent.
[Official Gazette September 30, 1941.]

DISCLAIMER

2,047,863.—*William G. H. Finch*, New York, N. Y., TELECOMMUNICATIONS SYSTEM.
Patent dated July 14, 1936. Disclaimer filed September 3, 1941, by the assignee, *Finch Telecommunications, Inc.*

Hereby enters this disclaimer to claims 1, 4, 5, and 9 of said patent.
